United States Patent Office.

CHARLES P. MOYER, OF WOMELSDORF, PENNSYLVANIA.

Letters Patent No. 70,600, dated November 5, 1867.

INSTRUMENT FOR ADMINISTERING BALLS TO HORSES.

The Schedule referred to in these Letters Patent and making part of the same.

TO ALL WHOM IT MAY CONCERN:

Be it known that I, CHARLES P. MOYER, of Womelsdorf, in the county of Berks, and in the State of Pennsylvania, have invented certain new and useful Improvements in Device for Administering Balls to Horses; and do hereby declare that the following is a full, clear, and exact description thereof, reference being had to the accompanying drawings, and to the letters of reference marked thereon.

In the annexed drawings, making part of this specification, A represents a shallow metallic cup with a double rim. Between the rims of this cup is placed and secured the rim of a rubber cup, E. The rubber cup is made from two to three inches deep, and tapering and more pliable toward its bottom. That half of the rubber cup toward the cup A is made of sufficient thickness as not to yield readily, while the other half is pliable, so that it can be drawn into the first half, as seen in the figure, leaving or forming a recess, as seen from x to x' x'. The cup A has secured to it a tube, B, upon which is secured a metallic shield, C. D represents a plunger, which passes through the tube B, and which has its inner end made fast to the bottom of the rubber cup E. By the use of the plunger the pliable half or the bottom of the cup E may be drawn into the other half, or thrown out, as may be desirable, this latter position being represented in red line in the figure.

When a ball is to be administered to a horse, the plunger is drawn outward, as seen, drawing the pliable bottom of cup E within its other half. The ball is then placed in the cup or recess, as seen at x and x' x''. The instrument is then placed within the horse's mouth, so that the shield will rest between the two jaws, keeping them apart. When the instrument has been properly adjusted, the operator forces the plunger inward, and thus discharges the ball into the throat or gullet of the horse. Balls may thus be administered to horses with great ease, and without danger to the operator.

Having thus fully described my invention, what I claim as new, and desire to secure by Letters Patent, is—

1. The India-rubber or pliable cup E, the cup A, and the plunger D, used substantially as and for the purpose set forth.

2. The shield C, in combination with the tube B and plunger D, when used as and for the purpose specified.

In testimony that I claim the foregoing I have hereunto set my hand this 3d day of August, 1867.

CHARLES P. MOYER.
